Patented February 14, 1905.

UNITED STATES PATENT OFFICE.

HOWARD S. HART, OF NEW BRITAIN, CONNECTICUT, ASSIGNOR TO THE HART & COOLEY COMPANY, OF NEW BRITAIN, CONNECTICUT, A CORPORATION OF CONNECTICUT.

DESIGN FOR A TOP PLATE FOR REGISTERS OR VENTILATORS.

SPECIFICATION forming part of Design No. 37,345, dated February 14, 1905.

Application filed February 1, 1902. Serial No. 92,218. Term of patent 14 years.

To all whom it may concern:

Be it known that I, HOWARD S. HART, a citizen of the United States, residing at New Britain, Hartford county, Connecticut, have invented a new, original, and ornamental Design for a Top Plate for Registers and Ventilators, of which the following is a specification.

In the accompanying drawings, Figure 1 is a perspective view of a top plate, illustrating

my new and original design. Fig. 2 is an end elevation of the top plate shown in Fig. 1.

What I claim is—

The ornamental design for top plate for registers or ventilators as shown.

HOWARD S. HART.
